UNITED STATES PATENT OFFICE.

WILLIAM J. DUVALL, OF ST. LOUIS, MISSOURI, ASSIGNOR TO SMITH & DAVIS MFG. CO., OF ST. LOUIS, MISSOURI, A CORPORATION OF MISSOURI.

CORNER FASTENER FOR BEDS.

Application filed May 7, 1923. Serial No. 637,239.

To all whom it may concern:

Be it known that I, WILLIAM J. DUVALL, a citizen of the United States, residing at St. Louis, State of Missouri, have invented 5 certain new and useful Improvements in Corner Fasteners for Beds, of which the following is a specification.

My invention has relation to improvements in corner fasteners or brackets for 10 beds, and consists in the novel details of construction more fully set forth in the specification and pointed out in the claims.

The object of the present invention is to provide a corner fastener of stamped metal 15 into which the bed side-rail may be quickly and securely fastened without the need of detachable parts; a further object is to provide a corner fastener that is simple and that may be cheaply constructed. Further 20 advantages will be better apparent from a detailed description of the invention in connection with the accompanying drawings, in which—

Figure 1 is a perspective view of a bed 25 showing my improved corner fasteners applied; Fig. 2 is an outside side elevation of the corner fastener; Fig. 3 is a bottom plan of the same; Fig. 4 is a vertical cross-section taken on the line 4—4 of Fig. 3; Fig. 5 is a 30 vertical longitudinal section on the line 5—5 of Fig. 3.

Referring to the drawings, H represents the head end of a skeleton bed and F the foot end, which are connected by side-rails 35 1, 1. The side-rails must be readily detachable from the end pieces of the bed for the purpose of setting up the bed and taking it down, consequently the corner fasteners 2, 2, etc., are secured to the bed posts P to 40 receive the ends of the rails 1. Formerly these corner fasteners or brackets were made of cast metal, but in recent years the corner fasteners have been variously made of stamped metal to obviate the necessity of 45 the foundry. Some of these corners are too complicated or have too many separable parts for practical use. My improved corner has but few parts, none of which need be removed to admit and fasten in place the 50 side-rail, as will be seen from the following description.

The corner consists of a housing 3, the rear wall 4 of which extends both above and below the housing proper to provide ears

4', 4' through which the corner is screwed 55 or otherwise secured to the bed-post P.

The housing is in the shape of an inverted letter U, i. e., it is open at the bottom, this open bottom being traversed by a brace 5 riveted into the sides of the housing. The 60 top wall of the housing is traversed by a rivet 6 near the rear wall 4, and a block 7 is loosely mounted on the rivet, there being a clearance space between the block 7 and the top wall of the housing 3 for a purpose 65 presently to appear. The brace 5 is provided with a tapped hole o through which is screwed a stud 8, the end of which is adapted to engage a recess r in the inwardly extending portion of the block 7. Two rivets 9 and 10 in spaced relation traverse the outside wall of the housing 3 about a distance from the top of the housing equal to half the width of a side-rail 1.

The rails 1 are angle irons, their legs a 75 and b are slotted at each end, leg a being provided with a short open slot 11, and leg b being provided with an open slot 12 of considerably greater length. The slot 12 is provided with a depression 13 at its closed 80 end, and with a depression 14 spaced therefrom a distance equal to that between rivets 9 and 10.

In setting up the bed, each end of the rails 1 is inserted into a housing 3 so that leg a 85 is in a horizontal plane and enters the space between the top of the housing and the block 7, the slot 11 receiving rivet 6. At the same time the vertical leg b will hug the side wall, having rivets 9 and 10 which will 90 enter slot 12 in this leg. However, the mere insertion of the rail end in this manner is not sufficient to hold it secure. The rail is firmly secured by screwing up the stud 8 as tightly as possible, which forces the block 7 95 against the leg a, raising the rail 1 so that the rivets 9 and 10 will enter the depressions 13 and 14, and firmly clamping leg a between block 7 and the top of the housing. The rail is now firmly held against movement in the housing in every direction.

In order to knock down the bed it is only necessary to loosen the stud 8 sufficiently to permit the rivets 9 and 10 to slip out of depressions 13 and 14.

Having described my invention, I claim:

1. In combination with a bed post and side-rail adapted to be secured thereto, a

corner bracket mounted on said post, said bracket comprising a housing, a block movable mounted within the housing adjacent the top wall thereof and in spaced relation therewith, a pin extending into the housing from a side wall thereof, one component of aforesaid rail being insertable between the block and top wall of the housing, the other having a slot for receiving the pin, and 10 means for simultaneously clamping said block against the rail and locking the rail to said pin.

2. In combination with a bed post and side-rail adapted to be secured thereto, a 15 bracket secured to said post, said bracket comprising a housing, a block movably mounted within the housing adjacent the

top wall thereof and spaced therefrom, a pair of pins extending into the housing from the side wall thereof, a brace traversing the open bottom of the housing, the aforesaid side-rail having component members, one of which is adapted to enter the space between said block and housing, and the other having a slot with spaced depressions, said slot being adapted to receive the aforesaid pins, and a stud traversing said brace and engaging the aforesaid block, the block operating to clamp one rail component and the pins entering the said depressions on screwing in the stud. 20 25 30

In testimony whereof I hereunto affix my signature.

WM. J. DUVALL.
